GRINDING MACHINE

Oliver E. Gaudreau and Henry Michelsen, Bristol, Conn., assignors to General Motors Corporation, Detroit, Mich., a corporation of Delaware

Application May 20, 1943, Serial No. 487,688

19 Claims. (Cl. 51—142)

This invention relates to grinding machines and particularly to machines which grind with an abrasive coated belt.

In the manufacture of antifriction bearing race rings and other annular work pieces which are to be mounted against a shaft shoulder, and particularly where a fillet is formed at the juncture of the shoulder with the shaft, it is desirable to cut away the sharp circular edge at the end of the shaft-receiving bore through the work piece so that the end face of the work piece may abut against the shoulder.

It is therefore an object of this invention to provide an improved machine which will quickly and easily remove the circular sharp edge where a bore cuts through a plane surface.

Another object is to provide an improved machine which simply and effectively chamfers the end of a bore through a work piece into merging relation with a flat surface on the work piece.

A further object resides in the provision of an improved machine for grinding the end of a bore through an annular member to produce a rounded chamfer of predetermined curvature and which blends with the bore and with a flat end face of the annular member.

To these ends and also to improve generally upon devices of this character, the invention consists in the various matters hereinafter described and claimed. In its broader aspects, the invention is not necessarily limited to the specific construction illustrated in the accompanying drawings in which:

Figure 1 is a front elevation of the invention;

Figure 2 is a fragmentary elevation of one side of the machine and including a schematic wiring diagram;

Figure 3 is a fragmentary side elevation of the other side of the machine;

Figure 4 is an enlarged fragmentary section taken along the line 4—4 of Figure 1; and

Figure 5 is a fragmentary perspective view showing the oscillating control mechanism.

Generally considered, a work piece, as the inner race ring W of an antifriction bearing, is rotatably supported about a vertical axis by a work holder or chuck 10 driven by a motor 11 which drives an abrasive coated belt 12 whose lower looped portion runs over a pivoted belt positioning device including pulleys carried by a support member or spider 14 that may be vertically moved and tiltably oscillated. Electrical control mechanism regulates the movement of the spider 14 to shift the abrasive belt into and out of abrading engagement with the circular

edge at the top of the bore through the work piece, and electric timers 15 and 16 are adjusted to control the time of grinding as well as the time of oscillation of the spider 14 so that the abrasive belt will grind a required chamfer at the end of the bore, and this chamfer is preferably rounded into blending relation both with the bore and with the flat upper end face of the work piece.

In the illustrated embodiment, the motor 11 is mounted on top of a hollow frame 20 provided with ways 21 upon which slides a vertically adjustable table 22 having a downwardly extending through bore 24. An antifriction bearing 26, mounted on the table, rotatably supports the chuck 10 which has a vertical through bore 27 coaxial of the bore 24 and preferably larger than the bore through the work piece W which is demountably supported coaxially of the chuck by a plurality of adjustable chuck jaws 28. A sleeve extension of this chuck projects through the bore 24 and protects the bearing 26 and other moving parts. A motor pulley 29 belt-drives a dual pulley 30 fastened on a shaft 32 which is journaled in a housing 33 that is secured to the table 22, and a pinion 34, secured to this shaft drives a ring gear 35 fastened to the chuck 10. The housing 33 and a hub on the pulley 30 extend through frame slots which are of a size to allow for the required vertical adjustment of the table, and a suitable idler pulley belt take-up (not shown) maintains the belt in proper driving engagement with the pulley 30. Vertical adjustment of the table 22 and of the chuck 10 is effected by rotation of a vertical feed screw 36 threaded through bosses in the housing 33 and supported at its upper end for freely rotatable non-axial movement in a frame projection 37. A hand wheel 38 turns a cross shaft 40 in frame-supported bearings, and a gear 42 secured to this shaft drives a gear 43 fastened to the feed screw 36.

A lateral frame extension 45, overlying the chuck 10, has a pair of spaced guide ways 46 which receive a vertically movable slide 47, and a stud 48 laterally extending out from the lower end of this slide, rotatably supports a rearwardly extending hub 50 of the oscillatable spider 14 which is generally T-shaped with a cross arm 51 and a central downwardly extending leg 52 beneath the hub 50. The abrasive belt 12, which is driven by a motor pulley 54, runs over pulleys 55 journaled on studs adjustably clamped in slots 56 at the ends of the cross arm 51, and the bottom of the lower looped portion of the belt 12 is positioned by a pair of spaced pulleys 57 rotatably supported by studs laterally projecting from the lower ends of

a pair of adjacent depending arms 58 that are pivoted at their upper ends on studs 59 secured to the leg 52. Adjustment of the spacing of the pulleys 57 is accomplished by locating the arms 58 in desired angular relation and securing them in position by screws 61 passing through arcuate slots in these arms and threaded into the leg 52, and laterally engageable arm abutments limit the minimum spacing of the pulleys 57 as illustrated in Figures 1 and 5. The adjustment of the pulleys 55 and 57 relative to the spider 14 controls the angle of grinding engagement of the abrasive belt with the work, and the spacing of pulleys 57 is preferably so adjusted that the looped portion of the belt does not engage the work until the bottom of the belt run lies considerably below the work piece as illustrated in Figure 1.

A bracket 62, on the frame 20, has an upstanding arm on which is pivotally supported the lower head of a cylinder 63 that contains a piston connected to a piston rod 64 slidable through a stuffing box in an upper head of the cylinder. The upper end of this piston rod is pivotally connected to the upper end of an arm 65 whose lower end is secured to a shaft 66 journaled in a frame projection 67, and an arm 68, fastened at one end to this shaft, has its other end pivotally connected to a link 69 journaled on the stud 48. Fluid under pressure, such as compressed air, fed from a suitable source through a supply pipe 70, is selectively directed by a reversing valve 72 through one of a pair of flexible ducts 73 and 74 into the upper or lower ends of the cylinder 63 to control the lowering and raising of the slide 47 and spider 14 for bringing the abrasive belt 12 into and out of grinding position, and fluid exhausted from the cylinder 63 through the other duct is directed by the reversing valve out of a pipe 75. As will be later described, the spider 14 during its vertical movement is prevented from rocking movement and is maintained in a horizontal position.

A lever 76, pivotally connected at one end to an operating stem of the reversing valve 72, has its other end connected through a pivot link to the movable armature of a solenoid 77, and an intermediate portion of this lever, which is slotted to fit over a post, is pivotally and yieldably supported by a coiled spring 78 loosely surrounding this post. A nut and washer on the post adjustably secure the lever 76 against the spring 78. When the solenoid 77 is deenergized, a spring (not shown) shifts the armature and the reversing valve stem to their illustrated positions wherein fluid pressure is directed through the duct 73 into the upper end of the cylinder 63 to raise the slide 47 to the top of its movement and to locate the abrasive belt above grinding position so that a work piece W may be inserted in and removed from chuck supported engagement. Electric control mechanism, to be later described, energizes this solenoid to shift the reversing valve and bring the abrasive belt downwardly into grinding position as shown in Figure 1. A belt tightener, which maintains the abrasive belt in desired running tension irrespective of the position of the spider 14, has a belt engaging pulley 79 rotatably supported on the upper end of an outwardly urged arm 80 which is secured at its lower end to a shaft 81 journaled in the frame projection 67, and a pulley segment 82, fastened to this shaft, is urged downwardly by a cable pulled by a weight 83, the upper end of this cable being secured to the segment 82.

and running in an arcuate groove in this segment.

An upwardly extending and rearwardly offset spider projection 85 (Fig. 4) overlies the hub 50 and is provided with a through slot in which is slidably received a locking bar 86 for movement radially of this hub to selectively engage within a vertical slot 87 in an arcuate plate 88 secured to a lateral projection 90 of the slide 47 or to engage within a slot 91 in the arcuate upper end of an oscillated rocker member 92 journaled on the hub 50. For clarity of illustration, Figure 5 shows the locking bar 86 midway of its movement between the slots 87 and 91. To facilitate engagement and disengagement of the locking bar in these slots and to assure positioning of the spider 14 relative to the arcuate plate 88 or relative to the rocker member 92, the side walls of the slots are preferably tapered to receive tapered ends on the locking bar. The underside of the plate 88 and the arcuate upper end of the rocker member 92 are substantially concentric with the stud 48 and in closely spaced relation to the spider projection 85 so that the locking bar may slide along one of these surfaces and be guided into one of the slots 87 or 91 in the event that the locking bar is not initially aligned with the slot into which it is to be received.

A lever 94, pivotally supported intermediate of its ends on a cross pin 95 for rocking movement in an opening through a boss 96 on the spider, has a rounded inner head seated in a vertical slot in the locking bar 86, and the outer end of this lever is connected through a short pivot link to the vertically movable armature of a solenoid 98 fastened to the front of the spider 14. A coiled spring 100 loosely received in a vertical bore of the boss 96 is compressed between an adjustment screw 101 and the lever 94 to normally urge the armature out of the solenoid 98 and to urge the locking bar 86 downwardly for engagement in the slot 91. A driving belt 103 from the dual pulley 30 drives a pulley 104 secured to a shaft 105 that is journaled in bearings on the frame 20, and a driver plate 106, fastened to this shaft, carries an eccentric crank pin 107 adjustably positioned in a transverse slot by a screw 108. A connecting rod 109, journaled at one end on the crank pin 107 and at its other end on a stud 110 projecting from the rocker member 92, translates the crank pin movement to oscillation of the rocker member. The connecting rod 109 may be adjusted as to length so that with different crank pin adjustments the spider 14 may be tilted to the same extent each side of its central horizontal position. A suitable idler pulley belt take-up (not shown) maintains proper driving belt engagement with the pulleys 30 and 104.

In operation, current from a suitable power line 115 passes through a main switch 117 and is selectively connected by the switch arm 118 and a contact 119 of a quick acting relay 120 to directly energize the solenoid 98, or by this switch arm and a contact 121 to put this solenoid under control of the electric timers 15 and 16. The main switch 117, which normally remains closed, is only opened when the machine is to remain idle for a considerable time, or, this switch may be opened to provide an emergency stop for the machine. Prior to starting the machine, the relay 120 is deenergized and current flows from the closed switch 117 through the wire 116, contact 119, switch arm 118 and wires 122, 123 to energize the solenoid 98 which acts through the lever 94 to hold the locking bar 86 seated in the

slot 87 and secure the spider 14 in its non-oscillating horizontal position of Figure 1. A switch 124, normally urged to a closed circuit position and mounted on the slide 47 above the arcuate plate 88, has a depending operating stem 125 which is engaged by the top of the locking bar 86 to shift this switch to open circuit position only when the locking bar is seated in the slot 87. The solenoid 77 and the relay 120, which are connected in parallel, are initially deenergized as shown in their full line positions of Figure 2, and fluid pressure is directed by the reversing valve 72 into the top of the cylinder 63 which results in locating the spider 14 in its upper position with the abrasive belt 12 lifted out of grinding position.

A work piece W is mounted in the chuck jaws 28 and the starting button 126 is pressed to close the switches of a controller switching mechanism 127 which operates in a standard manner (not shown) to release an electrically controlled motor brake 128 and to start the motor 11, the closing of these switches being effected by the energizing of a magnetic switch control coil s from wires 129 and 131. The closing of the starting button circuit also simultaneously starts both timers 15 and 16 from their initial zero positions and energizes the solenoid of a time-delay relay 130 to delay the closing of a switch 132 until the motor, abrasive belt 12 and work piece W have attained full speed. These timers and the solenoid of the time-delay relay are each connected across the wires 129, 131. When the starting button 126 is released, the circuits controlled by this button are held closed during timer control by a switch *t* in the timer 16. While this timer 16 operates, a switch arm *a*, connected to a wire 136, is held in engagement with a contact point connected to the wire 129. The time-delay relay is illustrated as including the tungsten lamp T and the carbon lamp C to regulate the delay in closing switch 132, but any suitable time-delay relay may be employed. The closing of the switch 132 simultaneously energizes the high speed relay 120 and the solenoid 77 from the wires 129, 131. At this time, the solenoid 77 reverses the valve 72 causing a downward feed of the spider to its bottom position to locate the abrasive belt 12 in work-grinding engagement. The energizing of the relay 120 causes a sufficiently rapid shifting of the switch arm 118 to the contact 121 to transfer control of the solenoid 98 to the timers while maintaining the locking bar 86 in the slot 87. Current now flows from the wire 136 through the normally closed switch *v* of the timer 15 and through a wire 137 to the contact point 121, through arm 118, and wire 122 thus placing solenoid 98 under timer control.

Each of the timers may be of a standard construction wherein a self-starting electric clock is provided with a sweep second hand 134 and an adjustable hand 135 which may be manually preset to determine when the timer switches are to be operated. The adjustment of the timer 15 controls the grinding time before oscillation of the abrasive belt, and the timer 16 is adjusted to control the extent of the entire grinding period including the time of oscillation. In the event that no oscillation is desired, the timer 16 is preset to operate for the same period as that of the timer 15. When oscillation is desired, after a predetermined time dependent upon the setting of the hand 135 on timer 15, the switch *v* is opened and breaks the circuit to the

solenoid 98 causing the spring pressed lever 94 to shift the locking bar 86 out of the slot 87 and downwardly onto the rocker member 92 and into the slot 91 causing the spider 14 to be oscillated so that the belt 12 will grind the desired chamfer curvature in the end of the work bore. We preferably preadjust the pulleys 55 and 57 and regulate the extent of spider oscillation so that this chamfer curvature will blend both with the bore and with the end face of the work piece. This oscillation continues until the hands of timer 16 are correspondingly positioned whereupon the arm *a* breaks circuit from the contact connected with the wire 129 and momentarily makes circuit with a contact connected to the wire 122 causing the solenoid 98 to again become energized and to shift the locking bar 86 upwardly for engagement within its slot 87. At the completion of the timing cycle, when the timer 16 operates its switch *t*, electrical connections (not shown) but standard to timing devices, stops these timers and resets them back to their zero starting positions. When the arm *a* breaks contact from the wire 129, the closed switch 124 maintains a circuit across the starting button 126 through the wires 139, 140 and 136 so that the relay 120, solenoid 77, and time delay switch 130 remain in their same energized positions, and the controller switching mechanism 127 remains in its previously shifted closed circuit positions.

The seating of the locking bar 86 within its slot 87 again secures the spider 14 in its non-oscillating horizontal position and opens the switch 124 thereby breaking the circuit to the relay 120, solenoid 77, time delay switch 130 and to the magnetic switch control coils. The switch arm 118 of the now deenergized relay 120 rapidly shifts from contact 121 to contact 119 to transfer the solenoid 98 from timer control to main power line control with sufficient rapidity so that the locking bar 86 remains within its slot 87. The deenergized solenoid 77 returns to its illustrated position of Figure 2 and allows the valve 72 to reverse causing an upward movement of the slide 47 and spider 14 to their top positions to lift the abrasive belt out of grinding position. Since the switch 124 cannot be opened until the spider 14 is locked in its horizontal non-oscillating position, the solenoid 77 will not be prematurely energized and the spider cannot be tilted while being lifted out of the work piece W with the consequent danger of breakage of the abrasive belt 12, spider 14 and work piece. The deenergizing of the time delay relay 130 returns the switch arm 132 to its initial open circuit position and at the same time the deenergizing of the magnetic switch control coil s permits the controller switching mechanism 127 to return to its indicated open circuit positions, so that the motor 11 is disconnected and the brake 128 is applied immediately after the abrasive belt is withdrawn from grinding position. The ground work piece W is removed from the chuck which has now stopped rotating and the machine parts are again ready for a duplicate operating cycle.

We claim:

1. In a device of the character indicated, a work holder for rotatably supporting a work piece having a bore, an abrasive belt provided with a looped portion receivable in said bore for grinding the work piece, belt driving means, feeding mechanism for feeding said looped portion into and out of grinding position, oscillating mechanism 70 for producing a relative oscillation between said

looped portion and said work piece during grinding, and means preventing simultaneous operation of the feeding mechanism and of the oscillating mechanism.

2. In a device of the character indicated, a work holder for rotatably supporting a work piece having a bore, an abrasive belt engageable with the work piece at an edge of said bore, belt driving mechanism, a belt guiding device including a member receivable within said bore, feeding means to enter said member within the bore for locating a running portion of the belt against the work piece, mechanism producing a relative tilttable oscillation between the belt guiding device and the work piece, and means preventing said oscillation during the feeding of said member into the work bore.

3. In a device of the character indicated, a work holder for rotatably supporting a work piece having a bore, an abrasive belt provided with a looped portion receivable in said bore for grinding the work piece, belt driving means, a pivotally mounted member, belt supporting pulleys adjustably mounted on said member for regulating the shape of said looped portion, and means for tiltably oscillating said pivotally mounted member during the grinding operation.

4. In a device of the character indicated, a work holder for rotatably supporting a work piece having a bore, an abrasive belt provided with a looped portion receivable in said bore for grinding the work piece, belt driving means, a pivotally mounted device for guiding the looped portion of the belt, mechanism for tiltably oscillating the pivotally mounted device, and means to regulate the extent of said oscillation.

5. In a device of the character indicated, a work holder for rotatably supporting a work piece having a bore, an abrasive belt provided with a looped portion, means to drive the belt, a pivotally mounted device for positioning said looped portion, feeding means for said pivotally mounted device to insert the looped portion into said bore to a grinding position and to withdraw the looped portion from said bore, mechanism for oscillating said pivotally mounted device during grinding, and means operated in timed relation to the feeding means for preventing said oscillation during the feeding movement of the looped portion into and out of said bore.

6. In a device of the character indicated, a work holder for rotatably supporting a work piece having a bore, an abrasive belt provided with a looped portion receivable in said bore, means to drive the belt, a pivotally mounted device for positioning the looped portion of the belt, mechanism to oscillate the pivotally mounted device, a member detachably locking the pivotally mounted device in a non-oscillating position, feeding means for producing a relative feeding movement between the pivotally mounted device and the work holder one towards and from the other, and control mechanism for simultaneously actuating said feeding means and for securing said member in its locking position.

7. In a device of the character indicated, a work holder for rotatably supporting a work piece having a bore, an abrasive belt provided with a looped portion, means to drive the belt, a pivotal device for positioning said looped portion, mechanism to oscillate the pivotal device, feeding means for feeding said device towards and from the work holder to insert the looped portion into grinding engagement within said bore and to withdraw the looped portion from said bore, and a member

selectively moved to hold said device in an intermediate non-oscillating position while said feeding means is operated and selectively moved to operatively connect said device to the oscillating mechanism during the grinding engagement of said looped portion with the work piece.

8. In a device of the character indicated, a work holder for supporting a work piece having a bore, a slide movable towards and from the work holder, a spider pivotally mounted on said slide, spaced pulleys adjustably positioned on said spider, an abrasive belt having a looped portion positioned by said pulleys and receivable in said bore, a pivotally mounted oscillating member located coaxially of said spider and having a slot, means providing a slot fixedly positioned with respect to said slide, a locking bar carried by said spider and selectively engageable with said slots, feeding mechanism for said slide to insert the looped portion of the belt into said bore to a grinding position and to retract the belt from said bore, and means securing the locking bar in said fixedly positioned slot whenever the feeding mechanism is operated.

9. In a device of the character indicated, a work holder for rotatably supporting a work piece having a bore, a slide movable towards and from the work holder, an abrasive belt provided with a looped portion, means to drive the belt, a pivotal device positioning said looped portion and supported for tilttable oscillation on said slide, an oscillatably driven member coaxial of the pivotal device and having a slot, means on said slide providing a slot in fixed relation to said slide, a locking bar slidably mounted on the pivotal device for selective engagement with said slots, feeding mechanism for the slide to insert the looped portion into said bore to a grinding position and to withdraw it from said bore, and means making said feeding mechanism inoperative whenever the locking bar is withdrawn from said fixed slot.

10. In a device of the character indicated, a work holder for supporting a work piece provided with an opening, an abrasive belt having a looped portion, feeding means for inserting the looped portion into work grinding engagement within said opening and for removing it out of work grinding engagement, and adjustable timing mechanism for said feeding means to control the time that said looped portion remains in said opening.

11. In a device of the character indicated, a work holder for supporting a work piece provided with a bore, an abrasive belt having a looped portion, belt driving means, feeding mechanism for inserting said looped portion to a work grinding position within said bore and for removing it from said bore, and adjustable timing means for controlling the feeding mechanism to remove the looped portion from said bore at the end of a predetermined grinding period.

12. In a device of the character indicated, a work holder for supporting a work piece provided with a bore, an abrasive belt having a looped portion, belt driving means, a belt guiding device for said looped portion, means for feeding the belt guiding device towards and from the work holder to insert the looped portion to a grinding position within said bore and to withdraw the looped portion from said bore, a timing mechanism for controlling the feeding means to determine the extent of time that the looped portion remains within said bore, and a control mechanism for causing the feeding means to insert said looped portion within the bore and for plac-

ing the feeding means under subsequent control of the timing mechanism.

13. In a device of the character indicated, a work holder for rotatably supporting a work piece having a bore, an abrasive belt provided with a looped portion receivable in said bore, belt driving means, a pivotally supported device for positioning said looped portion, means for feeding the pivotally supported device towards and from the work holder to insert the looped portion into and to withdraw it from said bore, mechanism for tiltably oscillating said pivotally supported device, and adjustable timing mechanism for controlling the extent of time that said pivotally supported device is oscillated.

14. In a device of the character indicated, a work holder for rotatably supporting a work piece provided with a bore, an abrasive belt having a looped portion receivable in said bore, belt driving means, a pivotally mounted device for positioning said looped portion, means for feeding said pivotally mounted device towards and from the work holder to insert the looped portion within said bore into work grinding engagement and to withdraw the looped portion from said bore, means to oscillate the pivotally mounted device during a portion of the time that the belt is in work grinding engagement, and adjustable timing mechanism for adjustably controlling the duration of said oscillation and for adjustably controlling the total grinding time.

15. In a device of the character indicated, a work holder for rotatably supporting a work piece provided with a bore, an abrasive belt having a looped portion, means to drive the belt, a pivotal device positioning said looped portion, feeding means for said pivotal device for inserting the looped portion into said bore to a grinding position and for withdrawing the looped portion from said bore, means to oscillate the pivotal device during a portion of the time the said looped portion is in grinding position, locking means preventing said oscillation during said insertion and withdrawal of the pivotal device, and adjustable timing mechanism adjustably regulating the extent of time that said looped portion remains in grinding position.

16. In a device of the character indicated, a work holder for a work piece provided with a bore, an abrasive belt having a looped portion receivable in said bore, a belt guiding device for said looped portion, belt driving means, starting mechanism for said belt driving means, feeding means for producing a relative feed between the belt guiding device and the work holder one towards and from the other for presenting the looped portion at a grinding position within said bore and for removing the looped portion from said bore, adjustable timing mechanism for controlling the operation of the feeding means which removes said looped portion from the work piece bore at the end of a predetermined time, and means responsive to the starting mechanism for controlling the operation of said feeding means which presents the looped portion within said

bore and for connecting said feeding means under subsequent control of the timing mechanism.

17. In a device of the character indicated, a work holder for a work piece provided with a bore, an abrasive belt having a looped portion, a belt guiding device for said looped portion, belt driving means, starting mechanism for said driving means, feeding means to produce a relative feed between the belt guiding device and the work holder one towards and from the other for inserting the looped portion to a grinding position within said bore and for withdrawing the looped portion from said bore, adjustable timing mechanism for controlling the operation of the feeding means which withdraws said looped portion from the bore at the end of a predetermined time, means responsive to the starting mechanism for controlling the operation of the feeding means which presents the looped portion within said bore and for connecting the feeding means under subsequent control of the timing mechanism, and mechanism under control of the starting mechanism for producing a predetermined delay in placing the feeding means under control of the starting mechanism.

18. In a device of the character indicated, a work holder for a work piece provided with a bore, an abrasive belt having a looped portion, a belt guiding device for said looped portion, a motor for driving said belt, motor starting mechanism, feeding means for moving the belt guiding device towards and from the work holder for inserting the looped portion into said bore to a grinding position and for withdrawing the looped portion out of said bore, adjustable timing mechanism for controlling the operation of the feeding means which withdraws the looped portion out of said bore, switching mechanism responsive to the motor starting mechanism for controlling the operation of the feeding means which inserts the looped portion into said bore and for starting said timing mechanism, and means producing a predetermined delay in the operation of said switching mechanism.

19. In a device of the character indicated, a work holder for rotatably supporting a work piece provided with a bore, an abrasive belt having a looped portion, belt driving means, a pivotal device guiding said looped portion, feeding means for said device for inserting the looped portion into said bore to a grinding position and for withdrawing the looped portion from said bore, means to oscillate the pivotal device during a portion of the time that the looped portion is in grinding position, locking means preventing oscillation of the pivotal device during said insertion and withdrawal of the looped portion and during a portion of the grinding period, and adjustable timing mechanism for regulating the duration of said oscillation and for regulating the extent of total grinding time.

OLOIVER E. GAUDREAU.
HENRY MICHELSSEN.
